MULTIPLE GRIP HANDLE

Filed Oct. 15, 1931

UNITED STATES PATENT OFFICE

HARRY S. JANES, OF SHANGHAI, CHINA

MULTIPLE GRIP HANDLE

Application filed October 15, 1931. Serial No. 568,917.

My invention relates in general to a multiple grip, and more specifically to a multiple grip handle for a golf club or other like devices. For ease of illustration I have chosen to show my improved multiple grip in connection with a golf club to which it is especially adapted. The handle or grip of my improved design permits a player to grasp a club with both hands in a natural manner and to swing the same accurately and with an ease hitherto impossible with the standard type of club handle.

As is well known to golf players, many difficulties, such as slicing, topping the ball, etc., are encountered by amateur players, due to the distorted position of the player's arms and shoulders occasioned by the necessity of grasping the single shaft of the club with both hands. It is apparent that with the present clubs, one hand must be above the other on the shaft of the club, and, therefore, one shoulder naturally assumes a position above the other. This grip also cramps the wrists and interferes with the free swing of the arms. All teachers endeavor to teach an overlapping or interlocking grip in order to compensate for this unnatural position of the hands on the club handle.

In the multiple grip which I have designed each hand assumes a natural position on a separate grip, the arms and shoulders are in like positions, and a free swing of the arms is permitted to aid in ease and accuracy of swing.

Among the objects of my invention are to provide a multiple grip for use with a golf club, cricket bat, or other like device having a separate handle for each hand;

To provide such a multiple grip in which the grips or handles lie parallel to each other or approximately parallel so that both hands assume like positions;

To provide an attachment consisting of an additional grip for use on standard clubs to provide a multiple grip; and to provide other features of improvement which will be further elaborated upon in the following detailed description. It will be understood that certain changes may be made in the

specific embodiments shown without departing from the spirit of my invention.

In the accompanying drawing:

Fig. 1 is a full view of a golf club provided with multiple grips in accordance with my invention, and showing the player's hands in the position they may occupy on the grips.

Figs. 2, 3, and 4 show successive stages in the forming of a multiple grip on a wooden shaft;

Figs. 5 and 6 show stages in the construction of a multiple grip on a steel shaft;

Fig. 7 shows a multiple grip attachment for a club;

Fig. 8 shows the clamping element for clamping the grip of Fig. 7 to a shaft;

Fig. 9 shows the device of Figs. 7 and 8 attached to a club shaft.

Referring to Fig. 1, I have endeavored to illustrate the principle of the invention applied to the "driver" or wood shaft golf club. At 1 and 2 are shown the two multiple grips arranged parallel to each other and side by side. The player's hands are shown grasping the two grips. The shaft 3 attached to the customary "head" 4 may be divided in any desired manner, such as illustrated in Figs. 2, 3, and 4. For instance, the wood shaft may be split or slotted as shown in Fig. 2, and the two sections 5 and 6 bent outward, as shown. An insert 7 may be placed in the crotch of the split portion and half-round inserts such as 8 and 9 may be applied to the two branches 5 and 6 to complete the rounded grips, as shown in Fig. 3. The complete assembly may then be glued in place and wound with strong twine, as shown in Fig. 4, and the grip or handles covered with leather or chamois as is customary with golf club handles. The parts 5 and 6 are bent back into parallel positions over the shoulder 7, as shown in Fig. 3, and held in this position by the winding, such as 10.

A multiple grip may be found on a steel shaft club, as shown in Figs. 5 and 6, in a somewhat similar manner by splitting the steel shaft 11 of the club, as shown in Fig. 5, and inserting an element such as 12 to 100

form the completely rounded multiple grips. The element 12 may be formed in any desired manner, and may be either welded to part 11 or riveted thereto. In either the 5 steel or wood shaft clubs the multiple grips may be arranged as shown in Fig. 6 with the grips at a slight angle relative to each other to compensate for different thickness of the fingers of the players—that is, one 10 with thick hands and fingers may grasp the club farther down at "a" while the player with slender hands may grasp the club at "b". The two ends of the multiple grip may be held together by an element, such as 13, which may be inserted into the ends of each grip 14 and 15 to hold them rigid.

In Fig. 7 I have shown an attachment in the form of an extra grip which may be secured to any club, as shown in Fig. 9, by 20 being clamped to the shaft thereof. It consists of the extra grip 16 wound to the proper size, a curved portion 17, and another part 18 of the clamp having holes 19 registering with the holes in part 17, through 25 which rivets or bolts and nuts may be inserted to clamp the grip to the club.

With two grips side by side as herein disclosed, the player may grasp the club with both hands in like position without changing the natural position of his shoulders, the hands will be close together, and yet each have a natural grip on the club. The shoulders will both have a like elevation and the "stance" or position taken by the player 35 when addressing the golf ball will be

natural and conducive to more accuracy and power, resulting in longer, straighter drives. Also, it should be understood that this type of multiple parallel grip may be applied to any device such as cricket bat, 70 baseball bat, or the like, and that various modifications may be made in the details shown without departing from the spirit of my invention.

Having fully described and ascertained the features and aspects of my invention, what I consider to be new and desire to have protected by Letters Patent will be pointed out in the appended claims.

What is claimed is:

1. A golf club having a shaft split at one end to form two half-round extensions, a pair of half-round inserts applied to the two extensions to form multiple grips, and leather wrappings around said extensions to form grips. 85

2. A golf club having a shaft split at one end into two parts, each part bent outward at like angles to the shaft and then back into substantially parallel relation to each other, inserts added to each part and wrappings around each part to form grips. 90

3. In a golf club, a shaft split into two sections bent outward and back together to form multiple handles parallel to each other, and means for holding the two handles in spaced relation and for preventing further splitting of the shaft. 95
